UNITED STATES PATENT OFFICE.

SHELBURN W. KENNEDY, OF HARRISBURG, PENNSYLVANIA.

TABLE.

Application filed June 4, 1923. Serial No. 643,382.

To all whom it may concern:

Be it known that I, SHELBURN W. KENNEDY, a citizen of the United States, residing at Harrisburg, in the county of Dauphin, 5 and State of Pennsylvania, have invented new and useful Improvements in Tables, of which the following is a specification.

The object of my said invention is the provision of a table adapted to be used to advantage as an ordinary table and also adapted to serve efficiently as a table for a bedridden invalid; the table top being adjustable horizontally relative to a supporting stand so as to rest above a bed, and being capable 15 of being readily increased or diminished in length as occasion demands.

Other objects and practical advantages of the invention will be fully understood from the following description and claim when 20 the same are read in connection with the drawings, accompanying and forming part of this specification, in which:—

Figure 1 is a view showing my novel table in full lines as properly arranged relative to 25 a bedstead shown by dotted lines, the top of the table being also shown by dotted lines as extended horizontally over the bed.

Figure 2 is a top plan view of the table with parts broken away.

Figure 3 is a detail vertical section of the bed, taken in the plane indicated by the line 3—3 of Figure 2.

Figure 4 is a top plan view of the top frame construction of the table, said frame being shown upon the stand.

Figure 5 is a similar view with the parts of the top frame in different positions, and with cross bars of the stand omitted.

Figures 6, 7 and 8 are enlarged detail vertical sections taken in the planes indicated by the lines 6—6, 7—7 and 8—8, respectively, of Figure 5.

Similar numerals of reference designate corresponding parts in all of the views of 45 the drawings.

Among other elements my novel table comprises a stand. The said stand is preferably made up of spaced parallel uprights 1, preferably, though not necessarily, with 50 pads 2, on their lower edges and cross bars 3 interposed between and fixedly connected to the uprights 1. Each upright 1 is provided at the outer side of its upper portion with a handle 4 for use when desired in facilitating 55 movement of the table. Each upright 1 is

also provided with a head 5, Figures 4, 5 and 8. The said heads 5 are provided at their outer sides with horizontal ribs 6 and at their inner sides with horizontal ribs 7.

The top frame construction of the table 60 comprises among other elements a rectangular frame member 8. Said rectangular frame member 8 is provided in its side bars with grooves 9 to receive the ribs 7 of the heads 5, whereby the frame member 8 is 65 supported on, but is free to be moved endwise relative to the said heads 5 and the uprights 1 of the stand. At the undersides of the cross bars of the members 8 are lugs 10, see full lines in Figure 3 and dotted lines 70 in Figures 4 and 5. The top plan construction also comprises two U-shaped members designated by 11 and 12, respectively. The said U-shaped members 11 and 12 are 75 slidably horizontally relative to each other and are also slidably horizontally relative to the heads 5 and the frame member 8. The U-shaped member 11 is provided with a slotted resilient strap 13 which extends inwardly from the middle of its end bar and is designed to receive in its slot the adjacent lug 10 on the frame member 8. Said straps are 80 preferably of metal and resilient to facilitate engaging the same with and disengaging them from the ends of the lugs, and they serve in practice to limit endwise outward movement of the U-shaped members 11 and 12. The U-shaped member 11 is also provided with side bars 14, the said side bars being 85 provided with inner and outer spaced end portions 15 and 16, and the outer end portions 16 being longer than the inner portions 15 in about the proportion illustrated in Figures 4 and 5. The outer portions 16 are 90 preferably, though not necessarily, separate pieces fixed to the major portions of the side bars 14. It will also be noticed that the side bars 14 are provided in their inner sides with longitudinal grooves 17 to receive the outer ribs 6 on the stand heads 5 so as to 95 permit of slidable movement of the U-shaped member 11 on the said heads, and also to enable the heads 5 to adequately support the U-shaped member 11. The U-shaped member 12 is provided with side bars 18. These 100 side bars 18 have reduced terminal portions 19 designed to be sheathed in the spaces between the portions 15 and 16 of the side bars 14 as shown in Figures 4 and 5. Said side bars 18 are also provided with grooves 20 110

to receive the outer ribs 6 of the heads 5, and fixed to the U-shaped member 12 and arranged at the inner sides of the side bars 18 thereof are side sections 21 which are movably arranged in grooves 22 in the outer sides of the side bars of the frame member 8, Figures 4, 5 and 7. Manifestly when the members of the top frame construction are assembled as illustrated the top frame construction can be arranged centrally above the stand as shown by full lines in Figure 1 and by full lines in Figure 4. It will also be noted that the top frame construction can be moved as a whole on the heads 5 of the stand uprights 1 so as to extend a considerable distance at one side of the vertical median line of the stand, as shown by dotted lines in Figure 1 and by full lines in Figure 5. In virtue of this latter capacity of the top frame construction, it will be appreciated that the table top may be extended so as to rest above a bedstead as shown by dotted lines in Figure 1, while the stand of the table rests against one side of the bedstead, and the inner portions of the lower ends of the stand uprights 1 extend under the bedstead. From this it follows that the portion of the table top remote from the vertical median line of the stand has capacity of sustaining great weight without liability of the table tipping. When it is desired to increase the length of the top frame construction one or both of the members 11 and 12 are drawn endwise outwardly, and when it is desired to diminish the length of the top frame construction, the said members 11 and 12 are relatively arranged as shown in Figure 4 and in full lines in Figure 5. By reference to Figure 5 it will be noticed that when the top frame construction is extended at one side of the vertical median line of the stand, the table top may be increased in length by moving the U-shaped section 12 and the frame member 8 toward the right into the positions shown by dotted lines in Figure 5, the strap 13 on the member 12 serving to pull the frame member 8 when the U-shaped member 12 is pulled toward the right. In addition to the top frame construction described the table top comprises sections 30 and 31 appropriately fixed on the U-shaped members 11 and 12, respectively. It will also be noted that the top section 30 is provided by preference with sockets 34 to receive dowel pins 35 on an extra leaf 36 which leaf 36 is provided, in turn, with sockets 37 to receive dowel pins 38 on the section 31. Thus when the length of the top frame construction is increased in the manner shown by dotted lines in Figure 5 the length of the table top may be increased by

the use of the supplemental leaf 36, Figures 2 and 3.

It will be apparent from the foregoing that while primarily designed for use in conjunction with a bedstead, my novel table is adapted to be used to advantage as an ordinary table, and it will also be noticed that the stand and the U-shaped members 11 and 12 may be so embellished as to enhance the ornamental appearance of the table and fit the same for use as a parlor table.

It will further be apparent from the foregoing that the table is simple and inexpensive in construction and is well adapted to withstand the usage to which tables are ordinarily subjected.

I have entered into a detailed description of the construction and relative arrangement of parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claim.

Having described my invention, what I claim and desire to secure by Letters-Patent, is:—

In a table, the combination of a stand having spaced upright side members with horizontal heads at their upper ends, said heads provided with horizontal ribs at their inner and outer sides; a rectangular top frame member having longitudinal grooves in the outer side of its side bars receiving the inner ribs on the stand heads and also having lugs at the undersides of their end bars, a U-shaped top member having longitudinal grooves in the inner sides of its side bars and also having inner and outer spaced terminal portions, the inner portions being shorter than the outer portions, a second U-shaped top member having longitudinal grooves in the inner sides of its side bars to receive the outer ribs on the stand heads and also having terminal portions to enter the spaces between the short and long terminal portions of the side bars of the first-named U-shaped member and further having sections disposed in the longitudinal grooves of the rectangular top member, slotted straps carried by the end bars of the U-shaped members and receiving the lugs on the end bars of the rectangular frame member and top sections carried by the said U-shaped members of the top.

In testimony whereof I affix my signature.
SHELBURN W. KENNEDY.
